UNITED STATES PATENT OFFICE.

GEORGE KEITH AND WILFRED AMBROSE WHATMOUGH, OF LONDON, ENGLAND.

LIQUID-FUEL VAPORIZER.

Application filed May 6, 1922. Serial No. 559,036.

To all whom it may concern:

Be it known that we, GEORGE KEITH and WILFRED AMBROSE WHATMOUGH, both subjects of the King of the United Kingdom of Great Britain and Ireland, and residing at London, England, have invented a certain new and useful Improvement in Liquid-Fuel Vaporizers, of which the following is a specification.

10 This invention relates to a liquid fuel vaporizer device adapted particularly for use in conjunction with means for controlling the supply of mixture to internal combustion engines as described, for example, in the specification of Letters Patent No. 1,817,709.

In the use of a vaporizer in connection with such automatic controlling means three problems have called for solution; firstly, the problem of rendering the vaporizer 20 itself sufficiently flexible in capacity to meet widely varying demands and at the same time capable of dealing with fuels of a comparatively high boiling point; secondly, the elimination of the trouble of "hunting"; and 25 thirdly, the prevention of flooding of the vaporizer and governor with liquid fuel in the event of the vaporizer not being hot enough to vaporize it or convert it into gas.

The requirements are answered by the device hereinafter described and illustrated diagrammatically in vertical section in the accompanying drawings.

The vaporizer is adapted to be heated by the exhaust gases and includes a metallic 35 heat exchanger structure having an inlet connection A for the exhaust gases located above a partition B having an aperture b through which the gases pass downwards, the partition B resting on a series of staggered metallic pins C or the like between which the gases pass in sinuous streams, and having a second aperture b' through which the gases flow upwards again to issue through an outlet connection D. This direction of flow of the gases is denoted by the line x—x on the drawing. The pins C 45 rise from a metallic plate E from which depends a solid portion F which dips into the liquid fuel and through which are formed a number of vertical sawcuts 2 interconnected at the upper end by a port G whence a pipe H passing through the apertured partition B carries off the vapor. A stop valve J controls the upward flow of vapor.

55 The solid portion F is surrounded by a cup K enveloped by lagging and having at

the lower end an extension K' which is fitted with some material of fairly good thermal conductivity and presenting a large surface, such as a suitable metal α in granulated form, or in the form of cuttings or other particles, with a layer L of wire gauze separating this material from the solid depending portion F.

60 The fuel is fed into the lower end of the extension K' through a hollow plug M provided with fine saw-slits.

The above described arrangement permits the maximum extraction of heat from the exhaust gases without interposing too high 70 a resistance, and the transference of this heat to the liquid in such wise as to insure a progressive action both as regards temperature change and area of surface.

75 The solid portion F will evidently become progressively cooler towards the bottom end, partly due to sluggishness in conductivity and partly due to the cooling effect of contact with the colder liquid. This circumstance by itself is not sufficient to prevent 80 the sudden flashing into vapor of the lighter fractions of the fuel on occasion, for which reason the extension K' is not surrounded by lagging so that it may become comparatively cool towards its lower end.

85 It will be seen that the large area of the saw-cuts 2 in the portion F presents a rapidly increasing heating surface to the fuel with a comparatively small increase in the bulk 90 of the fuel, so that upon a sudden demand for gas no time is lost in heating up the fuel, especially as there is a substantial storage of heat in the mass of metal forming the portion F.

95 Under certain conditions of running it is possible to set up quite a high suction on the outlet H of the vaporizer, and, if no provision were made to prevent it, it would be possible to pull the fuel in liquid form 100 through the vaporizer should there be insufficient heat to vaporize it. A fuel cup N having a float chamber is therefore located at some point outside the vaporizer at such a height that when the float valve closes the fuel does not rise above the level shown by the dotted line. This level is unaffected by 105 the suction, as the float chamber is placed in balance by means of a pipe O connecting the top of the chamber N with the upper part of the vaporizer and a pipe O' connecting the lower part of the said chamber to the bottom of the vaporizer. The float P is pref-

erably arranged to operate the valve Q directly, so that as the valve Q is pulled up it cuts off communication between the float chamber in the fuel cup N and the fuel supply R to a fuel tank. In the event of the float chamber and vaporizer being filled up with liquid when cold, and of the float-operated valve Q being closed in consequence, with the stop valve J also closed, 10 when the vaporizer begins to heat up, it would be possible to create a dangerous pressure within it. To obviate this the area of the valve Q is so chosen in proportion to the size of the float P that, should the pressure within the vaporizer rise more than a few pounds to the square inch, this pressure will overcome the lifting power of the float P and open the valve Q, permitting the liquid contained in the vaporizer and float 20 chamber to be blown back into the fuel supply tank through the pipe R until it is out of range of the heating elements in the vaporizer.

With this arrangement the fuel admission 25 to the vaporizer may be left permanently open, it being only necessary to open or shut the stop valve J to put the vaporizer in or out of action.

We claim:—

30 1. A liquid fuel vaporizer for internal combustion engines arranged to be heated by the exhaust gases of the engine, comprising a metallic heat exchanger adapted to be partly immersed in the liquid fuel and 35 presenting on its upper side a large surface for contact with the gases, said heat exchanger being constructed to divide the gases into sinuous streams and with an interrupted surface on its lower side to pre-

sent a large liquid contact surface, a float 40 chamber, a liquid fuel supply connection to said float chamber, a connection from the lower end of said float chamber to said heat exchanger and a connection from the upper end of said float chamber to said heat ex- 45 changer.

2. A liquid fuel vaporizer arranged to be heated by the exhaust gases including a heat-exchanging element comprising a metallic plate having, on its upper side, pins 50 between which the gases pass and having on the under side a solid portion intersected by cuts interconnected by a port and presenting a liquid contact surface, and a metallic substance in the form of particles contiguous 55 with said solid portion.

3. A liquid fuel vaporizer, arranged to be heated by the exhaust gases, including a heat-exchanging element comprising a metallic plate having on its upper side staggered pins between which the gases pass and 60 having on its under side a solid portion intersected by cuts interconnected by a port and presenting a liquid contact surface, a 65 connection for leading exhaust gases to the upper side of said plate, a connection for leading liquid fuel to the lower side of said plate, and a connection to said port for leading off vaporized fuel.

In testimony whereof we have signed our 70 names to this specification in the presence of two subscribing witnesses.

GEORGE KEITH.

WILFRED AMBROSE WHATMOUGH.
